FILING CABINET

Thomas J. Salsman, Chicago, and John Warren
Paxton, Bloomington, Ill.

Application April 22, 1944, Serial No. 532,280

3 Claims. (Cl. 45—2)

1

In the construction of filing cabinets for modern office use, it is imperative to conserve as extensively as possible the requirements for floor space. To that end resort recently has been made to side-filing cabinets wherein a plurality of containers, each formed of two right-angularly arranged lateral walls secured to two end walls, are swingably mounted in tiers in an open-front supporting casing so that the containers swing through an angle of 90° outwardly from a storage position into an access position wherein the containers are partly exposed through the open side of the casing beyond its front wall. With a view to making such floor-saving side-filing cabinets acceptably effective it has been found necessary to locate the pivots, about which containers are swingably mounted, some distance inwardly from the lower front corners of the containers so that when the containers are swung to open or access positions the center of gravity of each loaded container does not move too far forward in the casing. In fact, it is necessary to so arrange the connections, constituting the pivot about which a container revolves, that with several or all of the containers in a tier in their open positions they will not over-balance the casing and cause it to tip forward on its base. Also, it is necessary to make these containers as shallow as possible so that with two of the containers in their open positions the one above obscures as little as possible the visibility of the exposed indexes of the container below.

The main objects of this invention, therefore, are to provide an improved construction and arrangement of the containers and casing for filing cabinets of the aforesaid type so as to permit the use of shallow containers and thereby insure the greatest visual exposure of the contents of the under of two containers when swung to their open or access positions; to provide an improved shiftable casing section coacting with the container to complete a closure for the casing front when the container is in its storage position; to provide improved means for retracting said casing section to provide clearance for the container contents when the container is being shifted between its access and storage positions; and to provide improved coacting means on said casing and container for synchronizing the shifting of said casing section with the swinging of said container.

In the particular embodiment of this invention shown in the accompanying drawing,

Figure 1 is a perspective view of a two-drawer side filing cabinet, the lower container being shown in its open or access position and the upper

5 container being shown in its closed or storage position;

Figure 2 is an enlarged transverse sectional view of the same taken on the line 2—2 of Figure 1;

Figure 3 is a fragmentary view illustrating the relative positions of the shiftable casing section and the container as the latter approaches or begins to recede from its closed or storage position.

10 A filing cabinet embodying the essential features of this invention comprises a casing 4, the front of which is more or less open, wherein are mounted several containers 5 on connections 6 providing pivots about which the containers are conveniently swung or tilted through an angle of 90° between their closed or storage positions and their open or access positions. A follower 7 is arranged in each of the containers whereby the 15 contents are held in proper vertical position regardless of the quantity of the material in the container. Sections or plates 8 are swingably mounted on the casing above each of the containers 5 so as to be shifted into position to complete the closure of the front of the casing when the container is in its closed or storage position but retractable from the path of the container contents as the container is swung between its storage and access positions.

20 The casing 4 may be constructed of wood or metal or any of their appropriate substitutes. It comprises the usual sides 9, back 10, top 11, and bottom 12. The open front of the casing is provided with top, bottom, and intermediate reinforcing cross-bars 13 which divide it into compartments for the reception of the containers 5. The various parts of the casing are reinforced by means of braces 14 placed at strategic points in the structure.

25 30 35 40 45 50 55 Each container 5 is made up of a pair of right-angularly arranged lateral panels 15 and 16 and a pair of end members 17. Each container is mounted on the connections 6 within a compartment between a pair of cross-bars 13 so that when the container is in its closed or storage position the front-bottom panel 15 coacting with the movable casing section 8 forms a complete closure for the casing opening. When a container 5 is swung through a 90° angle into its open or access position the front-bottom panel 15 extends horizontally through said opening partially forward and rearward of the cross-bars 13. Along its rear edge the panel 15 is recessed at 18 to provide for the reception of extensions on alphabetical guides of the type disclosed in the

copending application of Irving R. Cornish, Serial No. 514,789, filed December 18, 1943. The index tabs on these guides would be exposed diagonally opposite as indicated by dotted outline 19.

The connections 6 whereby the containers 5 are herein shown to be swingably mounted in the casing embody a cross link construction such as is disclosed in copending application of John Warren Paxton et al., Serial No. 484,392, filed April 24, 1943. The links 20 and 21 are set in recesses in the ends 17 of the container 5 and have their upper ends pivotally connected thereto. The lower ends of the links are pivotally connected to the inner face of the casing sides 9 and rest on cradle blocks 22. This cross link arrangement thus supports each container on a pivotal relationship with respect to the casing so that the center of gravity of a loaded container during the swinging operation will always be kept rearwardly of the front face of the casing 4. Accordingly, even if all the containers in a tier are swung to their open positions they will not overbalance and tip over the cabinet.

The follower 7 as herein shown is constructed in accordance with the disclosure made in the copending application of John Warren Paxton et al., Serial No. 518,566, filed January 17, 1944. It is movable laterally of the container so as to support any quantity of contents in the container in a proper vertical position.

Each of the sections or plates 8 is pivoted or hinged at 23 directly inward of the adjacent reinforcing cross-bar 13 and is caused to swing between its vertical and retracted positions by means of a spring-actuated arm 24 as determined by the contact therewith of a shoulder 25 located on the container 5. The arm 24 is pivoted intermediate its ends at 26 on the inner face of one of the casing sides 9 and has a pin 27 at the upper end slidably engaging a slot 28 formed in a plate 29 secured to the end of the section 8. A spring 30 normally pulls the arm 24 rearwardly so as to swing the section 8 rearwardly into a horizontal position when the shoulder 25 is disengaged from the lower end of the arm 24. When the lower end of the arm 24 is engaged by the shoulder 25 the section 8 is shifted into its vertical position. The relative lengths of the two sections of the rocker arm 24 are such that a small movement of the lower or shorter section causes a proportionately greater movement of the longer or upper section. Consequently, the swinging of the section 8 is very rapid as the container 5 recedes from or approaches its closed position. Thus, no matter how quickly a container may be swung forwardly from its closed position, the section 8 will be positively retracted from the path of the contents of the container. The outer limit of travel of the container contents, to which the swing of this auxiliary section 8 must be accommodated, would be an arc on an axis from a point between the pivots of the lower ends of the links 20 and 21 and the upper-inner corner of the tab guide 19.

Such an arrangement of the section 8 permits the bottom-front panel 15 of the container 5 to be made considerably shorter than is possible with the structure shown in the aforesaid copending application of Paxton et al., Serial No. 484,392. The resulting advantage is that when two or more of the containers are in their open or access positions, the indexes for the lower container are more completely visible than if the bottom-front panel 15 had to be extended to include the width of the section 8.

The operation of the device will be more or less apparent from the foregoing description.

Although the invention has been herein illustrated and described as applied to a filing cabinet of the construction disclosed in the aforesaid copending application of Paxton et al., Serial No. 484,392, it will of course be understood that the invention is applicable to cabinets of other constructions in which the storage containers are movably mounted in other ways. Accordingly, changes in the described construction may be made without departing from the spirit of the invention, the scope of which should be determined by reference to the following claims, the same being construed as broadly as possible consistent with the state of the art.

We claim:

1. A filing cabinet comprising, a casing having a vertical front provided with a rectangular opening therein, a container mounted in said casing and having a rectangular face panel which in the normal storage position of said container extends in a vertical plane and serves as a closure for said opening and which container is adapted to swing outwardly in said opening through an angle of 90° to an access position in which said panel extends horizontally through, and across the bottom of, said opening, so as to locate a substantial portion of said container inside of said casing, connections supporting said container on said casing to permit the swinging of said container between its access and storage positions, an auxiliary section hinged on said casing for movement between a position in vertically-aligned registration with said panel to complete the closure of said casing opening when said container is in its closed position and a retracted position to clear the path of said container contents during the swinging of said container, shiftable means on said casing connected to said section and normally actuated independently of said container to shift said auxiliary section into its retracted position, and other means on said container positioned to engage said first-mentioned means when said container is in its fully-closed position so as to hold said auxiliary section in its position aligned with said container panel.

2. A filing cabinet comprising, a casing having a vertical front provided with a rectangular opening therein, a container mounted in said casing and having a rectangular face panel which in the normal storage position of said container extends in a vertical plane and serves as a closure for said opening and which container is adapted to swing outwardly in said opening through an angle of 90° to an access position in which said panel extends horizontally through, and across the bottom of, said opening, so as to locate a substantial portion of said container inside of said casing, connections supporting said container on said casing to permit the swinging of said container between its access and storage positions, an auxiliary section hinged on said casing for movement between a position in vertically-aligned registration with said panel to complete the closure of said casing opening when said container is in its storage position and a retracted position to clear the path of said container contents during the swinging of said container, a rocker arm pivoted on said casing and connected to said section, yielding means normally actuating said arm to retract said section from its vertically-aligned position with said container panel, and a shoulder on said con-

tainer adapted to contact said arm to hold said section in its position aligned with said container panel when said container is in its storage position.

3. A filing cabinet comprising, a casing having a vertical front provided with a rectangular opening therein, a container mounted in said casing and having a rectangular face panel which in the normal storage position of said container extends in a vertical plane and serves as a closure for said opening and which container is adapted to swing outwardly in said opening through an angle of 90° to an access position in which said panel extends horizontally through, and across the bottom of, said opening, so as to locate a substantial portion of said container inside of said casing, connections supporting said container on said casing to permit the swinging of said container between its access and storage positions, an auxiliary section hinged at its upper edge on the casing front so as to swing between a position in vertically-aligned registration with said panel to complete the closure of said casing opening when said container is in its storage position and a retracted position to clear the path of said container contents during the swinging of said container, a rocker arm pivot-

ally connected at its intermediate ends to said casing and having its outer end slidably connected to said auxiliary section, a spring normally urging said rocker arm to retract said section from its vertically-aligned position with said container panel, and a pin on said container adapted to contact the inner end of said rocker arm so as to cause it to shift said auxiliary section into said position vertically aligned with said container panel when said container is in its storage position.
